PACKET DISPENSING DEVICE

Alfred E. Ischinger, Mount Penn, Pa., assignor
to Narrow Fabric Company, West Reading, Pa.,
a corporation of Pennsylvania

Application January 13, 1933, Serial No. 651,531

5 Claims. (Cl. 206—44)

This invention relates to a new packet display and dispensing device particularly adapted for use in connection with packaged articles, such as shoe-laces and the like, and to a novel blank from 5 which the same is formed.

In order to facilitate merchandising shoe-laces, it has been found desirable to package the same in pairs, and to put a definite number of such packets in display containers for the convenience 10 of the retail trade. Heretofore, such containers were provided in the form of cardboard boxes having openings covered with translucent or transparent material through which the shoe-lace packets could be seen; the packets being 15 withdrawable, one by one, either through one of the flapped ends of the box, or through a reduced opening which necessitated flexing or bending of the packets and usually caused disturbance of the orderly stacked arrangement of the packets 20 within the container.

Some of the objects of my invention are, to provide a novel and simple display and dispensing device of this general type in which the above mentioned detrimental features are eliminated; 25 to provide means therein whereby the individual shoe-lace packets are successively positioned to facilitate direct inspection and longitudinal withdrawal from the container; and to form such a container from a novel flat blank of material.

30 The invention comprises the display and dispensing device for shoe-lace packets and the like, having the novel elements, features of construction and arrangement of parts in cooperative relationship as hereinafter more fully set forth; 35 and the novel blank from which the device is formed.

Other objects and attendant advantages will become readily apparent from the following detailed description of several embodiments of my 40 invention illustrated in the accompanying drawings, in which:

Figure 1 is a perspective view of my novel container and dispensing device, partly broken away to illustrate certain means adapted to partially 45 and successively project the shoe-lace packets therefrom.

Fig. 2 is a longitudinal sectional view of the device shown in Fig. 1, taken as indicated by the arrows 2—2 on said figure, and shows the same 50 supported in normal position, ready for use.

Fig. 3 is an enlarged sectional view taken as indicated by the arrows 3—3 on Fig. 1, and shows a packet of shoe-laces projectively positioned to permit ready inspection, and withdrawal from 55 the container.

Fig. 4 is a sectional view, similar to Fig. 3, but of a modified form of my invention and shows the lower sections of two adjacent walls of the container cut away to facilitate gripping and withdrawing a packet of shoe-laces longitudinally 5 from the container.

Fig. 5 shows a flat blank form from which the container of Figs. 1, 2 and 3 is produced.

Figs. 6 and 7 illustrate, on an enlarged scale, 10 different modifications of a certain cam abutment-member forming part of my invention.

Referring to the drawings, the shoe-lace display and dispensing device 10, indicated in Figs. 1, 2 and 3, comprises a packet container including a rear wall 11, provided at its upper end with an 15 extension 11a having therein an aperture 11b for suspending the device in upright position, as by a nail 12; a front wall 13 having therein one or more inspection windows or openings 14; a sheet of transparent material 22, such as "Cellophane" and the like, secured to the inside of front wall 13 for closing the openings 14; side walls 15 and 15a; a bottom closure member 16; a closure flap 17 at its upper end; a cam-abutment member 18 positioned to coat with shoe-lace packets 25 19; and a packet discharge opening 21 in side wall 15.

The shoe-lace packets 19 comprise shoe-laces 19a and 19b suitably secured together by a wrapper 19c, which preferably extends around the central portion of the packet so that the merchandise is exposed at the ends thereof, the whole constituting an unwrapped, or partially wrapped, elongated, flexible unit.

The device 10 is filled by inserting the individual packets 19 through the upper openable end of the container, the flap 17 is then closed and the device is uprightly positioned in accordance with Fig. 2 by suspending it from the nail 12 secured in a wall or other support 23. When so positioned, the weight of the upper packets 19 is imposed on the lowermost packet. Pressure exerted upon this packet causes end 19e thereof to coat with the inclined surface 18a of cam abutment 18 (see Fig. 3,) whereby motion is imparted to 35 this packet causing it to move longitudinally a limited distance relative to the next adjacent packet. Packet end 19f will then issue from device 10 through discharge opening 21 and project a short distance therebeyond. The limit of 40 movement is reached when end 19e reaches the bottom of incline 18a of cam abutment 18, and the lowermost packet 19 assumes the position clearly shown in Figs. 1 and 3. When this position is reached the packet end 19f projects from 45 50 55

device 10 sufficiently to readily permit direct inspection of the shoe-laces 19a and 19b, and manual engagement of the packet 19 for removal by longitudinal movement, as indicated by the arrow 5 in Fig. 3.

When the lowermost packet 19 is withdrawn through discharge opening 21, the next adjacent packet 19 coacts with cam-abutment 18, and its end is automatically issued through discharge 10 opening 21, as previously set forth, and this co-action between shoe-lace packets 19 and cam-abutment 18 automatically continues whenever a packet is removed from device 10, until finally but one packet remains which in turn is similarly 15 partially projected, or issues, from device 10 inasmuch as it is of sufficient weight to effect the desired coaction with cam-abutment member 18.

Fig. 4 illustrates a modified form of the invention, the parts corresponding to those of the device shown in Figs. 1, 2 and 3 being indicated by corresponding reference numerals. In this instance, however, the abutment member 18 of the previously described construction is omitted from the device 10 so that the shoe-lace packets 19 25 simply come to rest on the bottom member 16, and all the packets are constantly maintained in aligned stacked relationship with respect to each other. To facilitate withdrawal of the lowermost packet, the discharge opening 21 is enlarged by extending it along the rear wall 11, as at 21a, a suitable distance, and rendered of sufficient height to permit ready grasping of the packet end 19f.

Both of the described forms of my novel device 35 may be formed from a flat blank 25, shown in Fig. 5, and of material such as cardboard and the like. The blank is stamped or punched in a blanking operation, singly or in multiples, and has a configuration in accordance with the outline described by the solid lines; the dot-and-dash lines 25a indicating the lines of folding. The blank 25 comprises a rear-wall part 30, which is connected to a front wall part 31, by a bottom part 32. Rear wall part 30 has integrally formed 40 therewith side wall parts 30a and 30b, the former ending above part 32 and the latter having an extension or tab 33 extending therebeyond which is severed from parts 32 and 30 by a cut 34. Front wall part 31 is provided with one or more openings 35 and has integrally formed therewith a closure flap member 31a and side wall parts 31b and 31c; parts 31b and 30a ending at equi-distant points from part 32, thereby providing a notch 45 in the left blank edge which forms the discharge opening 21 of the finished container 10. Flap members 31d and 31e are provided at the ends of parts 31b and 31c and the latter has its opposite end terminating at the bottom forming part 32 of the container.

Before folding the blank 25 along the dot-and-dash lines 25a, a piece of transparent or translucent material, such as "Cellophane" or the like, is secured to the front wall part 31 of the blank to close the windows or openings 33 therein. In 55 constructing the device of Figs. 1, 2 and 3, the blank 25 is folded along the dot-and-dash lines 25a whereupon the parts 30a and 30b form the inner, and parts 31b, 31c the outer portions of side walls 15 and 15a of the device 10; and parts 30, 31 and 32 form the rear, front and bottom thereof respectively.

It should be noted that the cam-abutment member 18 is integrally formed with the container 10 in that the extension or tab 33 on the 75 side strip 30b of the blank 25 is bent inwardly

to position the same across the bottom right hand corner of the container 10; the extension part 33a being bent under to rest on bottom member 16 to which it may be secured with adhesive material if desired.

The cam-abutment 18 may also be separately formed of a solid right triangular shaped piece of material such as wood, as shown at 36 in Fig. 7, and will function equally well if constructed of a strip of suitable flexible material, shaped as 10 shown at 37 in Fig. 6; the bent ends 37a and 37b of the latter being secured to side wall 15a and bottom part 16 of the inside lower right hand corner of the device 10.

Although the device has been shown as designed for suspension from a support, it may be supported in other suitable ways; its packet feeding action not being changed so long as it is maintained in an upright position. It is also to be understood that the device specifically shown 20 and described can be modified in various ways without departing from the invention herein disclosed, and hereinafter claimed.

I claim:

1. A dispensing device, for elongated flexible 25 packets, formed from a blank including integral front and rear wall parts and an intermediate bottom part, and opposite side wall parts on each of said front and rear wall parts, one of the side wall parts of each of said rear and front 30 wall parts at one side of the blank being cut away at a point short of said bottom part to provide a cut-out opposite the latter, said front and rear wall parts being folded toward each other and the pairs of side wall portions at each side being inturned and secured one to another to form the body of the packet, said cut out portions thereby forming a side wall packet discharge opening, and one of the opposite side wall portions including a tab portion extending toward 40 said discharge opening and being arranged to constitute an inclined packet actuating cam member.

2. A dispensing device, for elongated flexible 45 packets, formed from a blank including integral front and rear wall parts and an intermediate bottom part, and opposite side wall parts on each of said front and rear wall parts, one of the side wall parts of each of said rear and front 50 wall parts at one side of the blank being cut away at a point short of said bottom part to provide a cut-out opposite the latter, said front and rear wall parts being folded toward each other and the pairs of side wall portions at each side being inturned and secured one to another to form the body of the packet, said cut-out portions thereby forming a side wall packet discharge opening, one of the opposite side wall portions including a tab portion extending toward 55 said discharge opening and being arranged to constitute an inclined packet actuating cam member, and an extension on the free end of said tab portion adapted to be secured to the bottom part of the dispensing device.

3. A dispensing device comprising a sheet-material receptacle having integral front, rear and bottom-wall portions and opposite side-wall elements on each of the front and rear portions, one of which on each of the front and rear portions at one side of the receptacle is shorter adjacent to the bottom than the corresponding elements at the other side to provide a discharge opening, and one of the elements at said other side of which includes an inclined tab by which 70 75

an article in the receptacle is deflected toward the discharge opening.

4. A device, for dispensing a plurality of elongated articles arranged side-by-side in substantially the form of a flat rectangular panel, comprising a sheet-material receptacle substantially conforming to said panel for mounting with the articles therein in horizontal position parallel to the bottom of the receptacle disposed one above another, the receptacle having parallel-plane front and rear walls holding the articles in said position on a bottom wall operatively integrally joining said front and rear walls, and opposite side-wall elements operatively integrally joined to each of said front and rear walls, one of which on each of the front and rear walls at one side of the receptacle adjacent to corresponding ends of the articles is shorter adjacent to the bottom wall than the corresponding elements at the other side of the receptacle to provide an opening for discharging the articles lengthwise one at a time, and one of the elements at said other side of which includes an operatively integral inclined tab by which an article in the receptacle is deflected lengthwise into said opening to have one end protrude therefrom by engagement of its other end with said tab and the urge of its own weight or the weight of one or more of the other articles thereon.

5. A device, for dispensing a plurality of elongated articles arranged side-by-side in substan-

tially the form of a flat rectangular panel, comprising a sheet-material receptacle substantially conforming to said panel for suspension from a top extension with which the rear wall of the receptacle is provided with the articles in horizontal position parallel to the bottom of the receptacle therein disposed one above another behind a window with which the front wall of the receptacle is provided, the receptacle having parallel-plane front and rear walls holding the articles in said position on a bottom wall operatively integrally joining said front and rear walls, and opposite side-wall elements operatively integral joined to each of said front and rear walls, one of which on each of the front and rear walls at one side of the receptacle adjacent to corresponding ends of the articles is shorter adjacent to the bottom wall than the corresponding elements at the other side of the receptacle to provide an opening for discharging the articles lengthwise one at a time, and one of the elements at said other side of which includes an operatively integral inclined tab by which an article in the receptacle is deflected lengthwise into said opening to have one end protrude therefrom by engagement of its other end with said tab and the urge of its own weight or the weight of one or more of the other articles thereon.

ALFRED E. ISCHINGER. 30
